UNITED STATES PATENT OFFICE.

JAMES McINTOSH, OF NORTH BRADDOCK, AND JOHN W. MILLER, OF CLAIRTON, PENNSYLVANIA.

COKE-OVEN-DAMPER VALVE.

Application filed October 10, 1923. Serial No. 667,743.

This invention relates to by-product coke ovens, and more particularly to means for flushing the damper valves of said ovens and cooling the gases prior to their entrance 5 into the collecting main.

One object of the present invention is to provide a continuous flow of flushing liquor to the damper valves of by-product coke ovens.

10 Another object is to provide a novel form of damper valve and fluid supply nozzle adapted to co-operate to form a spray of flushing fluid in the valve casing, thus flushing said casing and cooling the gases prior 15 to their passage into the collecting main.

By-product coke ovens to which this invention particularly pertains are composed of horizontal coke ovens built in batteries, with the ovens or coking chambers arranged 20 side by side. The ovens are usually tightly closed during the coking period and each oven has an offtake or stand-pipe which conducts the hot gases evolved in the coking process away from the oven. The stand-pipe, 25 usually located at one end of the oven, conducts the hot gases to a damper valve casing, from which they enter a collecting main common to a plurality of ovens. When an oven is open to the atmosphere for pushing, 30 charging or standing empty, it is usually shut off from the collecting main. That is, the damper valve is closed.

The gas which leaves the ovens carries considerable tar and this tar forms a deposit 35 on the damper valves and seats, so that in many instances the damper valves become stuck and are hard to open, with the result that much valuable gas is lost, since the ovens cannot be closed to the atmosphere 40 for any length of time without the damper valves being open when the oven is charged. If the damper valve should remain closed and the oven is closed to the atmosphere and coking is going on, a high gas pressure 45 results which will damage the oven walls. The present invention provides means for preventing the deposit of tars on the damper valves and seats and, therefore, eliminates sticking of these valves.

50 The gases, which are evolved during the coking process, leave the ovens or coking chambers at a high temperature and the first step in recovering by-products is to reduce the temperature of the gases so as to cause 55 a condensation of the tar oils. Material ad-

vantages in operation result from effecting this reduction of temperature quickly and as soon as possible after the gases leave the ovens. The present invention provides for the cooling of the gases prior to their entrance 60 into the collecting main.

In the drawings, Figure 1 is a somewhat diagrammatic plan view of a portion of a battery of coke ovens having this invention applied thereto.

Figure 2 is a front elevation thereof.

Figure 3 is a sectional elevation through one of the damper valves, taken on the line III—III of Figure 1.

Figure 4 is a similar elevation taken on 70 the line IV—IV of Figure 1.

Referring more particularly to the drawings, the numeral 2 designates the battery of ovens as a whole, which have coking chambers 3. A stand-pipe or ascension pipe 75 4 extends upwardly from the one end of each of the ovens or coking chambers 3 and is connected with a damper valve casing 5, which has an outlet 6 opening through a fitting 7 into a collecting main 8 which extends along the whole battery of ovens. 80

The valve casing 5 is provided with a valve seat 9 around the outlet 6 and a vertically operable damper valve 10 is mounted in the casing 5 and adapted to be engaged with the seat 9 to close the oven off from the collecting main when the oven 85 is open to the atmosphere.

The valve 10 is provided with a seat bearing flange 11 adapted to engage the valve 90 seat 9 and a downwardly extending circular skirt 12.

A suitable flushing fluid pipe or conduit 14 extends along the ovens and is adapted to have a cooling and flushing fluid passed 95 therethrough under pressure. Branch conduits 14^a lead from the pipe 14 to a point adjacent each valve casing, and a nozzle pipe 15 leads from the branch conduits 14^a through the fitting 7 below each of the valve casings 5 and terminate in an upwardly projecting nozzle portion 16.

The cooling and flushing fluid under pressure passes through the pipes 15 and nozzles 16 and is forced upwardly against the damper valves 10. As the fluid or liquid strikes the bottom of the valves 10 it will spread outwardly with considerable force against the skirt 12, which will baffle the fluid and cause it to fall downwardly in a 110

curtain-like spray so as to flush the interior of the valve casing and valve seat, thus removing any tar deposits and also materially cooling the gases, as they must pass through the spray of cooling and flushing fluid to enter the collecting main.

The skirt 12 also serves to limit the outward spread of the cooling and flushing fluid as it strikes the lower face of the valve, 10 and thus prevents the fluid entering the stand-pipes 4.

From the above it will be readily seen that we have provided an effective means for cooling the gases prior to their entering the collecting main, by compelling them to pass through a curtain of sprayed cooling and flushing fluid, and also that we have provided an effective means for preventing the accumulation of tar deposits on the 20 valve seat or within the valve casing.

While we have shown only one embodiment of our invention we do not wish to be limited thereto, since various modifications may be made without departing from 25 the scope of the invention as defined in the appended claims.

We claim:—

1. A damper valve for by-product coke ovens, comprising a casing having an inlet 30 opening adapted to be connected with a stand pipe leading from an oven and an outlet opening adapted to be connected to a gas collecting main, a valve member adapted to move vertically in said casing, a seat 35 for said valve, a nozzle pipe extending into said casing and adapted to project a stream of flushing fluid upwardly into said valve casing and against the bottom of said valve when said valve is in either open or 40 closed position, and means on said valve for preventing said fluid from entering said inlet opening and for causing said fluid to fall downwardly from said valve in the form of a spray.

2. A damper valve for by-product coke ovens, comprising a casing having an inlet opening adapted to be connected with a stand pipe leading from an oven and an outlet opening adapted to be connected to 50 a gas collecting main, a valve seat around

the outlet opening in the casing and a valve member adapted to engage the seat and close the outlet opening, a nozzle pipe below said valve seat and adapted to project a stream of flushing fluid upwardly into said valve casing and against the bottom of said valve when said valve is in either open or closed position, and means on said valve for preventing said fluid from entering said inlet opening and for causing said fluid to fall downwardly from said valve in the form of a spray.

3. A damper valve for by-product coke ovens, comprising a casing having an inlet opening adapted to be connected with a stand pipe leading from an oven and an outlet opening adapted to be connected to a gas collecting main, a valve seat around the outlet opening in the casing and a valve member adapted to engage the seat and close the outlet opening, a nozzle pipe below said valve seat and adapted to project a stream of flushing fluid upwardly into said valve casing and against the bottom of said valve when said valve is in either open or closed position.

4. A damper valve for by-product coke ovens, comprising a casing having an inlet opening adapted to be connected with a stand pipe leading from an oven and an outlet opening adapted to be connected to a gas collecting main, a valve member adapted to move vertically in said casing, a seat for said valve, a nozzle pipe extending into said casing and adapted to project a stream of flushing fluid upwardly into said valve casing and against the bottom of said valve when said valve is in either open or closed position, and a downwardly projecting skirt on the bottom face of said valve adapted to intercept the fluid after it strikes said valve, and to cause it to fall downwardly from said valve in a curtain-like spray, through which the gases passing through the outlet opening into the collecting main must pass.

In testimony whereof, we have hereunto set our hands.

JAMES McINTOSH.
JOHN W. MILLER.
